UNITED STATES PATENT OFFICE.

JOHN H. KING AND EDWARD M. WOLFE, OF BEAVERFALLS, PENNSYLVANIA,
ASSIGNORS OF ONE-THIRD TO GEORGE H. BLAXTER, OF PITTSBURG,
PENNSYLVANIA.

MILL FOR ROLLING SEAMLESS TUBING.

SPECIFICATION forming part of Letters Patent No. 718,476, dated January 13, 1903.

Application filed October 19, 1901. Serial No. 79,212. (No model.)

To all whom it may concern:

Be it known that we, JOHN H. KING and EDWARD M. WOLFE, citizens of the United States, residing at Beaverfalls, in the county of Beaver and State of Pennsylvania, have invented certain new and useful Improvements in Mills for Rolling Seamless Tubing, of which the following is a specification, reference being had therein to the accompanying drawings, forming part of this specification, in which—

Figure 1 is a front elevation of our improved tube-rolling mill. Fig. 2 is a plan view thereof. Figs. 3 and 4 are cross-sectional views on the lines III III and IV IV, respectively, of Fig. 2.

Our invention refers to improvements in mills for rolling tubes, rods, bars, &c.; and it consists in the construction and arrangement 20 of the rolls, their housings, connections, and driving mechanism, as shown in the drawings, whereby several sets of rolls are closely assembled and capable of performing a continuous series of rolling operations within a 25 restricted area and the shortest time.

Generally the mill consists of two lines of rolls A and B, parallel to each other and mounted in housings 2; which are closely adjacent, the inner legs of each set of housings 30 resting on a common rail 3 and at the outer sides upon the usual independent rails 4.

As will be observed, each alternate set of housings is mounted in staggered arrangement and in proper position for the location 35 therein of alternate pairs of grooved rolls 5, each pair being successively in alinement with the lines A or B, respectively. The result of this arrangement is that the pair of rolls on one side is located about midway between the pair of rolls on the opposite side or at a corresponding distance to one side or the other of the end rolls and housings.

All of the rolls are mounted upon the same level, as are their spindles 6 and 7, the 45 lower and upper spindles of each set being geared together by toothed gearing 8. Both lower spindles, or both upper, if desired, are driven in opposite directions by any suitable gearing 9 from a shaft 10 or other convenient 50 source of power or prime mover. As thus arranged, the rolls being rotated, as indicated

by the arrows, Figs. 3 and 4, the piece to be rolled is first introduced between the first pair of rolls a, passing inwardly between the spindles 6 and 7 through suitable or convenient guiding devices. The piece is then introduced between the pair of rolls b, passing inwardly between the spindles of the first pair of rolls, and this operation is repeated back and forth through rolls c and d until 60 the piece emerges from the last pair of rolls, when it may be taken to the finishing-rolls or elsewhere, as desired. It will be understood that the number of sets of rolls may be increased or diminished as desired and that 65 they may be assembled more or less closely adjacent to each other, according to the work in view. The mill is continuous in its operation, is very compact in construction, will effect a great economy in time and handling 70 of the pieces, and is simple and cheap in construction, while its advantages over a three-high mill or over two separate mills will be readily appreciated by all those familiar with the art of rolling tubes or other similar 75 articles.

Changes and variations may be made by the skilled mechanic in the details of construction or in the gearing by which the different sets of spindles are driven—as, for instance, 80 pulleys, pinions, or sprocket-wheels may be substituted for the bevel-gearing 9, driven from a single prime mover through belting, cables, toothed gearing, or chains in opposite directions; but all such changes are contemplated as within the scope of the following 85 claims.

Having described our invention, what we claim is—

1. In a rolling-mill, the combination of two 90 independent sets of roll-spindles and rolls, the rolls and spindles of one set being arranged in staggered relation to the rolls and spindles of the other set, with correspondingly-arranged housings, a driving element, and gearing connecting said driving element with the spindles of each set respectively, and necessitating the driving of said sets in opposite directions, substantially as set forth.

2. In a rolling-mill, the combination of two 100 independent sets of roll-spindles and rolls, the rolls and spindles of one set being arranged

in staggered relation to the rolls and spindles of the other set, with correspondingly-arranged housings, a driving element, and gearing connecting said driving element with the

5 spindles of each set respectively, and necessitating the driving of said sets in opposite directions, and at the same speed, substantially as set forth.

3. In a rolling-mill, the combination of two 10 independent sets of roll-spindles and rolls, the rolls and spindles of one set being arranged in staggered relation to the rolls and spindles of the other set, with correspondingly-arranged housings; a single driving element, 15 and intervening gearing by which movement is transmitted therefrom to each set of rolls in opposite directions, substantially as set forth.

4. In a rolling-mill, the combination of two 20 independent sets of roll-spindles and rolls, the rolls and spindles of one set being arranged in staggered relation to the rolls and spindles of the other set, with correspondingly-arranged housings and independent adjusting 25 means for each set of rolls; a single driving

element, and intervening gearing by which movement is transmitted therefrom to each set of rolls in opposite directions, substantially as set forth.

5. In a rolling-mill, the combination with 30 outer housing-supporting foundation-rails and an intermediate housing-supporting rail; two independent sets of housings mounted upon the outer and intermediate rails respectively, two independent sets of roll-spindles 35 and rolls mounted in said housings, whereby the rolls and spindles of one set are arranged in staggered relation to the rolls and spindles of the other set, a driving element, and gearing connecting said driving element with the 40 spindle of each set respectively, substantially as set forth.

In testimony whereof we affix our signatures in presence of two witnesses.

JOHN H. KING.
EDWARD M. WOLFE.
